UNITED STATES PATENT OFFICE.

SAMUEL A. HAMMONS, OF LEESVILLE, LOUISIANA.

RAIL-JOINT.

1,348,107.

Specification of Letters Patent. Patented July 27, 1920.

Application filed January 28, 1920. Serial No. 354,717.

To all whom it may concern:

Be it known that I, SAMUEL A. HAMMONS, a citizen of the United States, residing at Leesville, in the parish of Vernon and State of Louisiana, have invented a new and useful Rail-Joint, of which the following is a specification.

This invention relates to rail joints and particularly to that class wherein bolts are dispensed with.

10 The object is to provide a device for joining the ends of adjacent rails of tracks wherein a clamping action is brought to bear upon such ends for holding the same together, which clamping action becomes greater as the load is increased, as when a train of cars is passing over the same.

15 A further object is to provide means for accomplishing the above which may be easily applied to the ends of the rails in overlapping relation thereto, and comprising a pair of clamping members arranged upon either side of the web of the rail and caused, when under load, to wedge inwardly 20 and hug the latter in such manner as to rigidly hold the abutting ends in alinement.

25 A still further object is to provide means of this class which may be readily removed from its connection to the rails and as readily re-applied when desired.

30 A full and complete understanding of the invention may be obtained from a consideration of the following detailed description, taken in connection with the accompanying drawing forming a part of this specification, it being understood that while the drawing shows a practical form of the invention, the latter is not confined to strict conformity therewith, but may be changed or modified, 35 so long as such changes or modifications mark no material departure from the salient features of the invention, as specifically pointed out in the appended claims.

35 In the drawing, in which similar reference characters designate corresponding parts throughout the several figures,

40 Figure 1 is a perspective view of the end portions of abutting rails having the improved boltless connecting means applied thereto.

45 Fig. 2 is a transverse sectional view through the same.

50 Fig. 3 is a longitudinal, horizontal sectional view thereof.

55 Fig. 4 is a detail perspective view of one of the clamping members.

The rails 1, which may be of the ordinary standard size and shape, are placed together in the usual manner with the adjacent ends abutting, the point of juncture being located customarily between the ties, not shown in the drawing. It is to be understood that the improved joint may be used in conjunction with wooden, metal, concrete or any other kind of railroad tie.

60 Oppositely disposed wedging blocks or side members 2—2 arranged at either side of the web 3 of the rails are adapted, through means to be described, to be forced inwardly toward each other and against 65 said web with such force, when subjected to the load of a passing car, as to securely hold the two ends of the rails in alinement. These blocks or members extend longitudinally of the rails a considerable distance 70 beyond the joint which is located substantially in the center of said blocks, and the entire length of the latter may be such as to fit between two ties or, if desired, may be made longer so as to rest upon one or more 75 ties.

75 The blocks 2 have their upper edges 4 formed to fit beneath the head 5 of the rail, at each side, and the inner faces 6 of the said blocks are substantially vertical and fit 80 against the side faces of the web 3, as clearly shown in Fig. 2 of the drawing.

85 The outer faces of the blocks or members are inclined, as at 7, and merge, at their lower portions, into horizontally disposed 90 shelves 8, comprising the upper portions of outer surrounding walls 9 which lie at the outer edges of the bottom flanges or base 10 of the rails. Inwardly directed tongues 11 formed integrally with the blocks 2 are connected with the lower portions of the surrounding walls 9 and extend toward each other, the upper faces of the same fitting 95 snugly against the under face of the base of the rail and their adjacent inner edges lying 100 in spaced relation to each other near the center of said rail.

105 The cavity 12 thus formed in each block between the tongue 11 and the main body portion thereof is adapted to receive one of the outwardly extending flanges comprising the base 10 of the rail, said flange extending to the inner end of the said recess or cavity and the upper wall 13 of the latter is inclined as shown, at a greater inclination 110 than the upper face of the adjacent flange, so that a space is provided in order that the

block may not bind on the flange of the rail when a load is passing, as will become apparent. The lower faces 14 of the inwardly extending tongues 11 are inclined to correspond with the walls 13, and the cavity 12 extends from end to end of the block in order to accommodate the base of the rail throughout the length of the block 2.

A keeper plate 15, formed preferably of heavy sheet metal of sufficient strength and thickness to withstand the strain to which it is subjected, is adapted to co-act with the wedging blocks 2-2, to cause them to grip the web of the rails when under load, and to so engage the said blocks as to effectually prevent their becoming dislodged from their positions against the sides of the rail.

The keeper plate 15 is somewhat longer than the blocks 2-2 and is provided along its longitudinal edges with integral, spaced, upstanding walls 16 adapted to engage the outer faces of the surrounding walls 9 of the blocks and to hold the same against the outer edges of the rail flanges or base 10, the upper edges of the said walls 16 being bent inwardly toward each other as at 17 to engage over the top face of the ledge or shelf 8, as clearly illustrated in Figs. 1 and 2 of the drawing.

At each end the keeper plate 15 is provided with an extension, which is somewhat narrower than the width of the rail base, as indicated in dotted lines in Fig. 3 of the drawing, the said extensions having oppositely disposed lugs 18 located at their corners and adapted, after the keeper is in position, to house the wedging blocks, to be bent upwardly against the outer edges 40 of the rail base and then down upon the upper face of the same to securely hold the keeper in place upon the adjacent ends of the rails.

It will be seen, by referring to Fig. 2 of the drawing, that there is a space left between the upper faces of the rail flanges and the upper walls of the cavities 12, which corresponds with the space between the keeper plate 15 and the lower faces of the inwardly directed tongues 11, which spaces permit the blocks to rock sufficiently to give the desired clamping action of the blocks against the web of the rail, the outer lower edge of the blocks, where bearing 55 upon the plate 15 at the lower portion of the walls 16, acting as a fulcrum and permitting the tongues 11 to function as levers to throw the upper or body portions of the blocks toward each other and against the web of the rail, when a load is passing over the rail, as will be readily understood.

From the foregoing, it will be seen that a simple, cheaply manufactured and effective rail joint has been provided, entirely

eliminating the use of bolts or other similar fastening means, and which may be easily applied to the abutting ends of rails by simply sliding the wedging blocks within the space between the upstanding walls 16 of the keeper and the web of the rails, the wall 9 being located beneath the overhanging portion 17 of the keeper, and then by hammering or otherwise forcing the lugs 18 over and upon the flanges of the rails. The device retains its position upon the rails, and the more weight the same is subjected to, the greater will be the clamping action.

What is claimed is:—

1. A boltless rail joint comprising a pair of identical wedging blocks or side members adapted to lie at opposite sides of the webs of abutting rail ends and beneath the head of the rail, each block having a longitudinal cavity extending throughout its length for receiving the adjacent base flange of the rail, the upper walls of said cavities being spaced from the upper faces of the said flanges, the lower portions of the blocks below the cavities comprising tapered tongues extending toward but spaced from each other below the rail flanges, and means passing beneath the rail and embracing the blocks at the base and connecting the same together, the said blocks being adapted to have a rocking movement, when under a load, to clamp the rails and hold the same in position. 95

2. A boltless rail joint comprising a pair of identical wedging blocks or side members adapted to lie at opposite sides of the webs of abutting rail ends and beneath the head of the rail, each block having a longitudinal cavity extending throughout its length for receiving the adjacent base flange of the rail, the upper walls of said cavities being spaced from the upper faces of the said flanges, the lower portions of the blocks below the cavities comprising tapered tongues extending toward but spaced from each other below the rail flanges, a keeper plate arranged beneath the said tongues and having outer walls surrounding the lower portions of the blocks to prevent their spreading, means provided on the keeper plate to hold the said plate together with the blocks in position upon the rails, the said blocks being adapted to have a rocking movement, when under a load, to clamp the rails and hold the same in position. 110

3. A boltless rail joint comprising a pair of clamping blocks, each adapted to lie at opposite sides of the webs of abutting rail ends, said blocks having outer walls surrounding the flanges of the rails and carrying inwardly extending tongues lying beneath the rail flanges, said tongues ex- 125

tending the full length of the block and tapering toward their inner ends where they are spaced from each other, a keeper plate located beneath the tongues and having longitudinal walls at its outer edges abutting against the outer walls of the blocks and having inwardly directed portions overlying the blocks, and lugs located at the corners of the keeper plate and 10 adapted to be bent over and upon the rail

flanges to hold the plate and the blocks in position.

In testimony that I claim the foregoing as my own, I have hereto affixed my signature in the presence of two witnesses.

SAMUEL A. HAMMONS.
